FURNACE

Elmer H. Berryman, San Francisco, Calif.

Application February 13, 1937, Serial No. 125,617

7 Claims. (Cl. 22—69.1)

This invention relates to dental casting furnaces and is an improvement to the furnace disclosed in the Berryman Patent No. 2,017,337 of October 15, 1935.

5 In operating furnaces such as disclosed in my prior patent above referred to, some difficulty has been found in renewing or replacing the heating elements. In making castings under super-atmospheric pressure, it has been found that in 10 some instances the gasket disposed between the work supporting member, in which the investment ring is accommodated, and the lower face of the furnace is injured when the work supporting means is moved away from the furnace proper, due to the residual air pressure existing within the furnace. Furthermore, it has been found that when large investment rings are used such as shown in Figure 6 of my Patent No. 2,017,337 which cannot be entirely housed within the furnace, it is difficult to maintain the investment ring up to temperature. Consequently there is 15 a tendency for the investment to cool and shrink, making the mold smaller and causing the casting to be smaller than required.

20 One of the objects of this invention is the provision of a pneumatically operated dental casting furnace in which the heating element or elements may be readily changed or replaced.

25 Another object of the invention is the provision of a pneumatically operated dental casting furnace having means whereby the interior of the furnace may be vented to atmosphere before the furnace is opened, in order to prevent 30 injury to the gaskets.

35 A further object of the invention is the provision, in combination with a dental casting furnace, of a heater for surrounding the exposed surfaces of an investment ring when the investment ring is operatively associated with the furnace.

40 The invention possesses other advantageous features, some of which with the foregoing will be set forth at length in the following description where that form of the invention which has been selected for illustration in the drawings accompanying and forming a part of the present specification is outlined in full. In said drawings, one form of the invention is shown, but it is to be understood that it is not limited to 45 such form, since the invention as set forth in the claims may be embodied in a plurality of forms.

50 Referring to the drawings:

55 Figure 1 is a vertical section taken on the broken line 1—1 of Figure 4 with parts broken away

showing a dental casting furnace embodying the objects of my invention.

Figure 2 is a section taken on the line 2—2 of Figure 1.

Figure 3 is a section taken on the line 3—3 of Figure 1.

Figure 4 is a section taken on the line 4—4 of Figure 1.

Figure 5 is a section taken on the line 5—5 of Figure 1.

Figure 6 is a partial vertical section of a dental casting furnace in combination with a heating element surrounding a large investment ring when the investment ring is operatively associated with the furnace.

As shown in various figures of the drawings, my invention may be embodied in a dental casting furnace comprising a rectangular casing 1 provided on its lower face with a boss 2 through which a circular opening 3 is formed. The upper 20 face of the casing 1 is provided with a threaded nipple 4 adapted to receive a cap 5 and containing a sight opening 6. Secured over the upper end of the nipple 4 by means of the cap 5 is a sight glass 7. In order to make an air tight 25 joint between these members, gaskets 8 may be used as shown in Figures 1 and 5. One end of the casing 1 is provided with a flange 9 to which is detachably secured by any suitable means such as screws a cover plate 11. In order to hermetically seal the cover plate 11 to the flange 9, a gasket 12 may be interposed between these two members.

Snugly accommodated within the casing 1 and inserted therein through the flanged end of the 35 casing is a rectangular block 13 of any suitable refractory material. The block 13 is provided with a central sight opening 14 in registration with the sight opening 6 of the nipple 4, and the lower face of the block is provided with a recess 40 15.

It will be noted that the lower portion of the recess 15 is rectangular in form while its upper portion or ceiling is upwardly concave. Disposed within the recess 15 is a cradle or tray 16 formed on its upper face with a pair of 45 parallel spaced longitudinally extending semi-circular recesses 17 and 18. The tray 16 is also provided with a central vertical circular opening 19 in line with the sight opening 14 of the refractory block 13. Seated within the recesses 50 17 and 18 formed in the tray 16 are resistance elements 21 and 22, the extremities of which are of enlarged diameter as shown in Figures 4 and 5. By so constructing these resistance elements, their ends are snugly accommodated within their 55

- respective recesses and the electrical resistance at their ends is relatively low with respect to their central portions. The rear ends of the resistance elements 21 and 22 are connected by 5 means of a metal clip 23. The forward end of the resistance element 21 is secured by means of a metal clip 24 to a binding post 25 and the forward end of the resistance element 22 is secured by means of a clip 26 to a binding post 27.
- 10 The binding posts 25 and 27 are secured to and extend through the lower wall of the casing 1, as best shown in Figure 1. It will be noted that the clips 24 and 26 are apertured at their ends so as to tightly fit over the tapered upper ends 15 of the binding posts 25 and 27.

The casing 1 is supported by and secured to the legs 28 by means of screws 29, and the legs 28 are provided intermediate their ends with threaded lugs 31 to which is secured by means of 20 screws 32 a shelf 33. The shelf 33 is formed with a central bore 34 adapted to receive a screw 35 and with a counter-bore 36 adapted to rotatably receive the flange 37 formed on the upper end of an interiorly threaded sleeve 38. The 25 flange 37 is held in the counter-bore 36 by a plate 39 riveted to the shelf 33. Secured to the sleeve 38 by a pin 41 is a hand wheel 42. The screw 35 is formed with a longitudinally extending slot 43 adapted to receive a pin 44 secured to the 30 shelf 33. From this construction it will be noted that the pin 44 engaged within the slot 43 prevents the rotation of the screw 35 and that therefore the rotation of the hand wheel 42 will cause the screw 35 to travel in a vertical direction.

35 The upper end of the screw 35 is accommodated in a socket 45 formed in the lower end of a work supporting member 46 and is secured thereto by means of a pin 47. The upper face of the work supporting member 46 is recessed 40 to accommodate an annular gasket 48 and is formed with a counter bore 49 for accommodating an investment ring 51. The investment ring 51 is provided with an interrupted thread 52 adapted to be received in a complementary interrupted thread 53 formed in the bore 49. The 45 interrupted threads 52 and 53 form in effect a bayonet and slot connection and serve to quickly attach and detach the investment ring to and from the work supporting member. In order 50 to form a hermetical seal between the investment ring and the work support 46, an annular gasket member 54 is interposed between these two members. The floor of the work supporting member 46 is formed with a central recess 55 and communication between this recess and atmosphere is established by means of a passageway 56.

As shown in Figure 4, an air line 57 is secured to the casing 1 and establishes communication 60 with the interior thereof and a suitable source of super-atmospheric pressure through a two-way valve 58.

To operate the device as above described, the investment ring 51 is secured to the work supporting member 46. The gold button 59 is placed 65 in the depression in the investment material and the work supporting member is screwed and sealed against the boss 2 of the casing 1, all as shown in Figure 1. The binding posts 25 and 70 27 are then connected to a source of electric current and the interior of the furnace brought to a temperature sufficient to melt the gold button 59. The condition of the gold button may be observed through the sight glass 7, and when it is in a molten state, the valve 58 is so adjusted

as to permit air under super-atmospheric pressure to pass into the casing 1 and force the molten gold into the mold formed in the investment material. The air confined within the mold is thereby forced into the central recess 55 and 5 passes to atmosphere through the passageway 56. After the molten gold has passed into the mold formed in the investment material and it is thought that a well-defined inlay has been 10 formed, the valve 58 is adjusted so as to establish communication between the atmosphere and the casing 1, thereby equalizing the pressures on either side of the casing 1. When this has been done, the work supporting member 46 may be lowered by rotating the screw 42 and the investment ring 51 removed by a pair of tongs and quenched in the usual manner.

The ring 51 and the investment material contained therein expand with an increase in temperature. The investment material is so chosen 20 as to its coefficient of expansion that when the inlay molded in it cools to room temperature, the inlay will exactly correspond to the size of the cavity for which it was made. In order to maintain the ring and its contents to temperature, it is desirable as shown in Figure 1 that the openings 3 and 19 be sufficiently large to leave a space about the ring 51 for the free circulation of hot air.

In some instances it is desired to use an investment ring of such dimensions that it cannot be accommodated within the circular opening 3 formed in the bottom of the casing 1. An investment ring 61 of this character has been shown in Figure 6 as provided with an upwardly 35 extending conical neck 62. The lower end of the investment ring 61 is supported by the work supporting member 46 and is sealed thereto by means of the gasket 48, while its upper end is sealed against the boss 2 of the casing 1 by means 40 of the gasket 48'. It will be noted that although the conical neck 62 of the investment ring 61 extends through the opening 3 of the casing 1, the peripheral surface of the body of the investment ring falls entirely outside of the opening. 45 In order to maintain the body of the investment ring to temperature, so that the gold within the investment material will not cool and shrink, a cylindrical heating element 63 is made to surround the body of the investment ring. The cylindrical heating element 63 may be made of 50 either a refractory material or insulating material and has embedded in its inner surface a resistance wire 64 adapted to pass through a handle 65 and thereby be connected to any suitable source of electric current. It will be noted 55 that by this arrangement my casting furnace may be effectively used in connection with investment rings of such size that they cannot pass through the opening in the bottom of the furnace, and by the use of a cylindrical heating element surrounding the investment ring, the temperature of the investment ring may be maintained at any desired degree. The operation 60 of the furnace as shown in Figure 6 is identical with the operation of the furnace as shown in Figure 1 with the exception that the cylindrical heater 63 must of course be disposed over the investment ring before the investment ring is secured between the bottom of the casing 1 65 and the work supporting member 46.

I claim:

1. A casting furnace comprising: a casing having an opening in the bottom face thereof; a block of refractory material accommodated in 75

- 5 said casing and provided with a recess in registration with the opening in said casing; a tray of refractory material disposed in said recess and provided with a central opening in line with the opening in said casing; a resistance element supported on said tray; means for connecting said resistance element to a source of electric current; and means for holding an investment ring in registration with the opening in the bottom of 10 said casing.
- 10 2. A casting furnace comprising: a casing having an opening in the bottom face thereof and a detachable end wall; a block of refractory material accommodated in said casing and provided 15 with a recess in its lower face in registration with the opening in the bottom face of the casing; a tray of refractory material disposed in said recess and provided with a vertical opening in line with the opening in the bottom of the casing; a 20 resistance element supported on said tray in line with the vertical opening therein; means for connecting said resistance element to a source of electric current; and work supporting means adapted to be held against the lower face of said 25 casing in registration with the opening therein.
- 25 3. A casting furnace comprising: a casing having an opening in its bottom face and a detachable cover for one side thereof; a block of refractory material accommodated in said casing and 30 provided with a recess in its lower face in registration with the opening in the bottom face of the casing; a tray of refractory material disposed in said recess and provided with a vertical opening in line with the opening in the bottom of the 35 casing; a recessed seat formed in the upper face of said tray; a resistance element disposed in said recessed seat in line with the vertical opening in said tray; means for connecting said resistance element to a source of electric current; and work 40 supporting means adapted to be held against the lower face of said casing in registration with the opening therein.
- 40 4. A casting furnace comprising: a casing having an opening in its bottom face and a detachable cover for one side thereof; a block of refractory material accommodated in said casing and 45 provided with a recess in its lower face in registration with the opening in the bottom face of the casing; a tray of refractory material disposed in said recess and provided with a vertical opening in line with the opening in the bottom of the casing; a plurality of spaced recessed seats formed in the upper face of the tray; resistance elements disposed in said seats in line with the vertical 50 opening in the tray; means for connecting said resistance elements to a source of electric current; and work supporting means adapted to be held against the lower face of said casing in registration with the opening therein.
- 50 60 5. A casting furnace comprising: a casing hav- ing an opening in its bottom face and a detachable cover for one side thereof; a block of refractory material accommodated in said casing and provided with a recess in its lower face in registration with the opening in the bottom face of the casing; a tray of refractory material disposed in said recess and provided with a vertical opening in line with the opening in the bottom of the casing; a pair of spaced, parallel, longitudinally 55 extending recessed seats formed in the upper face of said tray; resistance elements disposed in said seats in line with the vertical opening in the tray; means for connecting said resistance elements to a source of electric current; and work supporting means adapted to be held against the lower face of said casing in registration with the opening therein. 10 15 20 25 30 35 40 45 50 55 60
- 60 7. A casting furnace comprising: a casing having a circular opening in its bottom face; a block of refractory material accommodated in said casing and provided with a recess in its lower face in registration with the opening in the bottom face of the casing; a tray of refractory material disposed in said recess and provided with a vertical opening in line with the opening in the bottom of the casing; an opening formed in one of the lateral faces of said casing and through which said block and said tray may be passed; a detachable cover secured over said last mentioned opening; a resistance element supported on said tray in line with the vertical opening therein; means for connecting said resistance element with a source of electric current; and work supporting means adapted to be held against the lower face of said casing in registration with the circular opening therein. 10 15 20 25 30 35 40 45 50 55 60
- 60 8. A casting furnace comprising: a casing having a circular opening in its bottom face; a block of refractory material accommodated in said casing and provided with a recess in its lower face in registration with the opening in the bottom face of the casing; a tray of refractory material disposed in said recess and provided with a vertical opening in line with the opening in the bottom of the casing; an opening formed in one of the lateral faces of said casing and through which said block and said tray may be passed; a detachable cover secured over said last mentioned opening; a resistance element supported on said tray in line with the vertical opening therein; means for connecting said resistance element with a source of electric current; a cylindrical investment ring of greater diameter than the diameter of the circular opening in the bottom face of said casing; means for holding said investment ring against the bottom face of said casing and in line with the circular opening therein; and a heating element surrounding said investment ring. 10 15 20 25 30 35 40 45 50 55 60
